[57] CLAIM

The ornamental design for an air flow director, as shown and described.

DESCRIPTION

FIG. 1 is a front perspective view of an air flow director, showing my new design;

FIG. 2 is a front elevational view;

FIG. 3 is a right side view, the opposite side being the mirror image thereof;

FIG. 4 is a top plan view thereof;

FIG. 5 is a back view thereof; and,

FIG. 6 is a perspective view thereof on a reduced scale mounted at the rear of a pickup truck bed.

The broken lines in FIGS. 5 and 6 are for illustrative purposes only and form no part of the claimed design.
